UNITED STATES PATENT OFFICE

145,477

DESIGN FOR A PENCIL SHARPENER

Jon W. Hauser, Oak Park, Ill., assignor to Sears, Roebuck and Co., Chicago, Ill., a corporation of New York

Application October 31, 1945, Serial No. 123,355

Term of patent 14 years

(Cl. D74—23)

To all whom it may concern:

Be it known that I, Jon W. Hauser, a citizen of the United States, and a resident of Oak Park, in the county of Cook and State of Illinois, have invented a new, original, and ornamental Design for a Pencil Sharpener, of which the following is a specification, reference being had to the accompanying drawings, forming a part thereof.

Fig. 1 is a side elevational view of a pencil sharpener showing my new design;

Fig. 2 is a plan view of the same embodiment; Fig. 3 is an end elevation of the same embodiment viewed from the operating handle end; and Fig. 4 is an end elevation viewed from the pencil opening end.

I claim:

The ornamental design for a pencil sharpener, substantially as shown.

JON W. HAUSER.
